UNITED STATES PATENT OFFICE.

WILLIAM P. BETTENDORF, DECEASED, LATE OF BETTENDORF, IOWA, BY JOSEPH W. BETTENDORF, ADMINISTRATOR, OF DAVENPORT, IOWA.

UNDERFRAME FOR CARS.

1,035,848.

Specification of Letters Patent. Patented Aug. 20, 1912.

Application filed October 26, 1910. Serial No. 589,097.

To all whom it may concern:

Be it known that WILLIAM P. BETTENDORF, deceased, late a citizen of the United States, residing at Bettendorf, in the county of 5 Scott and State of Iowa, did invent certain new and useful Improvements in Underframes for Cars, of which the following is a full, clear, and exact description.

This invention relates more particularly 10 to the underframes of railway cars, and particularly to the cars described and illustrated in an application for Letters Patent of the United States, filed by William P. Bettendorf, deceased, May 16th, 1910, Serial 15 No. 561558.

The principal object of this invention is 20 to obtain such a construction of the underframe that the center of gravity of the car can be lowered considerably, and yet possess that resiliency or yielding quality which it is 25 so desirable to have, particularly in steel cars.

A further object of this invention is to 25 obtain a strong and durable construction that can be economically made.

These and other objects are accomplished 30 by the means hereinafter fully described and as particularly pointed out in the claims.

In the drawings:—Figure 1 is a plan view 35 of a part of the metal frame of a car embodying this invention. Fig. 2 is a transverse vertical section of the same, taken on dotted line 2, 2, Fig. 1. Fig. 3 is a longitudinal vertical section, taken on dotted line 3, 3, Fig. 1.

The principal elements of the underframe to which this invention relates, comprise the body-bolsters, the center-sill and draft-sills, or equivalent structure therefor. The body-bolsters A are made of cast metal and I prefer to make them hollow in order to lessen their weight as much as possible. The outer ends of these body-bolsters are provided with integral brackets a, that extend 40 in a transverse upward direction to the running-board E of the car, which latter is riveted to the ends of the same.

At their centers of length the body-bolsters are provided with pockets B that extend lengthwise of the car in the vertical plane of the king-bolt C. These pockets are adapted to contain coiled springs or other suitable cushioning devices, substantially as set forth in the aforesaid original application. The underside of the bolster, A, at its

center of length, is provided with a male centering plate which is seated in the obverse centering plate of a suitable truck-bolster X. The rear side of this bolster is provided with wings D, D, the inner vertical surfaces of which are parallel and are arranged so as to be an equal distance from the vertical longitudinal plane of the king-bolt, and the upper flanges of these wings are bent outward and are otherwise constructed to afford means to which the flanges of a horizontally disposed I-beam center-sill F can be secured by rivets or otherwise. This horizontally disposed single I-beam center-sill extends longitudinally from one 60 body-bolster to the other, its web is horizontal and may be recessed as at F' at its ends to accommodate the central enlargements of the bolsters in which the pockets B are made, and likewise the devices used in 65 connection with said pockets. The upper flanges at the ends of the I-beam web are bent or curved outward, and are riveted or otherwise secured to the curved flanges of 70 the wings D, D. This bending of the flanges 75 of the wings D of the bolster, and the upper flanges of the center-sill enables the body of 80 the car to be lowered, and as the ends of these center-sill flanges abut against the rear 85 surface of the body of the bolster, the shearing strain on the rivets used to secure said flanges to said wings is avoided.

The front side of the body-bolster is provided with forwardly projecting draft-sill extensions, G, G, on each side of the vertical longitudinal plane of the center of length of the bolster. These extensions are, preferably, I-shaped in cross section and converge toward each other until they reach a point slightly to the rear of the draft-rigging (not shown). From this latter point 90 said draft-sills have their opposing inner surfaces parallel to each other, and provided with suitable integral stop-lugs f, for the 95 usual follower-plates of said draft-rigging, and have their forward ends connected by 100 a cross-member g, both above and below the draw-bar opening.

What I claim as new is:—

1. In a railway car, a center-sill consisting of a single integral I-beam, the web connecting the flanges of which is horizontally disposed and the upper flanges of which are flared outward.

2. In a railway car, a center-sill consist-

ing of a single integral rolled metal beam having a horizontally disposed web and upwardly projecting flanges that are flared outwardly.

5 3. In a railway car, a center-sill consisting of a single integral rolled metal beam extending from bolster to bolster and secured thereto having a horizontally disposed web and upwardly projecting flanges.

10 4. In a railway car, a center-sill consisting of a single integral rolled metal beam extending from bolster to bolster and secured thereto having a horizontally disposed web and upwardly projecting flanges, and 15 having openings adjacent the ends of its web.

5. In a railway car, a center-sill consisting of a single integral rolled metal beam having a horizontally disposed web and upwardly flared flanges.

20 6. In a railway car, a center-sill consisting of a single integral rolled metal beam having a horizontally disposed web and up-

wardly flared flanges and having openings adjacent the ends of its web.

7. In a railway car, a center-sill consisting of a single integral I-beam extending from bolster to bolster and secured thereto the web connecting the flanges of which is horizontally disposed and provided with 30 openings adjacent its ends.

8. In a railway car, a center-sill consisting of a single integral I-beam the web connecting the flanges of which is horizontally disposed and provided with openings adjacent its ends, and the upper flanges of which are flared outward.

Signed at Bettendorf, Scott county, Iowa, October 17th 1910.

JOSEPH W. BETTENDORF,
Administrator of the estate of William P.
Bettendorf, deceased.
